(57) **CLAIM**

The ornamental design for a high chair for a child, as shown and described.

DESCRIPTION

1. High chair for a child

1.1 : Perspective

1.2 : Front

1.3 : Back

1.4 : Left

1.5 : Right

1.6 : Top

1.7 : Bottom

1.8 : Enlarged

Figure 1.1 is a perspective view of a high chair for a child showing a new design; figure 1.2 is a front elevation view thereof; figure 1.3 is a rear elevation view thereof; figure 1.4 is a left side elevation view thereof; figure 1.5 is a right side elevation view thereof; figure 1.6 is a top plan view thereof; figure 1.7 is a bottom plan view thereof; and figure 1.8 is an enlarged view of the portion shown by means of a dashed curved line, circle and number 8 in figure 1.1; the broken lines illustrate portions of the high chair that form no part of the claimed design.
